(57) **CLAIM**

The ornamental design for an eye patch band, as shown and described.

DESCRIPTION

FIG. 1 is a first embodiment perspective view of an eye patch band, showing my new design in condition of use covering a user's right eye;
FIG. 2 is a front elevational view thereof;
FIG. 3 is a right side elevational view thereof;
FIG. 4 is a rear elevational view thereof;
FIG. 5 is a top plan view thereof;
FIG. 6 is a front elevational view thereof;
FIG. 7 is a bottom plan view thereof;
FIG. 8 is a rear elevational view thereof;
FIG. 9 is a right side elevational view thereof;
FIG. 10 is a left side elevational view thereof;
FIG. 11 is a second embodiment perspective view of an eye patch band, showing my new design in condition of use covering a user's left eye;
FIG. 12 is a top plan view thereof;
FIG. 13 is a front elevational view thereof;
FIG. 14 is a bottom plan view thereof;
FIG. 15 is a rear elevational view thereof;
FIG. 16 is a left side elevational view thereof; and,
FIG. 17 is a right side elevational view thereof.
The broken line showing of a head in FIGS. 1-4 and 11 illustrates environmental structure only and forms no part of the claimed design.
